(57) **CLAIM**

The ornamental design for a smart watch, as shown and described.

DESCRIPTION

FIG. 1 is a front perspective view of a smart watch showing our new design according to a first embodiment;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is an enlarged view of the portion 9 encircled in FIG. 1;

FIG. 10 is an enlarged view of FIG. 6;

FIG. 11 is an enlarged view of FIG. 7;

FIG. 12 is a front perspective view of a smart watch showing our new design according to a second embodiment;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof;

FIG. 19 is a rear perspective view thereof;

FIG. 20 is an enlarged view of the portion 20 encircled in FIG. 12;

FIG. 21 is an enlarged view of FIG. 17; and,

FIG. 22 is an enlarged view of FIG. 18.

The dashed broken lines in the figures depict portions of the smart watch that form no part of the claimed design. The

(Continued)

dot-dot-dash broken lines in the figures, encircling portions of the claimed design that are illustrated in an enlarged view, form no part of the claimed design.
